UNITED STATES PATENT OFFICE.

RAYMOND L. PLUMLEY, OF WILMINGTON, DELAWARE, ASSIGNOR TO FREDERICK OSANN COMPANY, OF NEW YORK, N. Y., A CORPORATION OF NEW YORK.

OVERSEAMING SEWING-MACHINE.

No. 897,486.

Specification of Letters Patent.

Patented Sept. 1, 1908.

Application filed July 18, 1907. Serial No. 384,329.

To all whom it may concern:

Be it known that I, RAYMOND L. PLUMLEY, a citizen of the United States of America, residing in Wilmington, in the county of 5 Newcastle and State of Delaware, have invented a certain new and useful Improvement in Overseaming Sewing-Machines, of which the following is a true and exact description, reference being had to the accompanying 10 drawings, which form a part thereof.

My present invention relates to sewing machines for overseaming of the type commonly called fur stitching machines. These machines as usually constructed comprise a 15 pair of feeding disks between which the work is gripped and intermittently advanced, a needle parallel to the plane of the disks and reciprocating in the direction of its length to carry its operating end back and forth across 20 the line at which the disks meet, and a looper which enters the loop of thread carried through the work by the needle and carries the loop back to the other side of the work into such a position that the needle passes 25 through the loop before entering the work in the formation of the next stitch. To perform these functions, the looper is given motions in three directions, one parallel to the motion of the needle, one toward and away 30 from the plane of the feeding disks, and one in the direction parallel to the common tangent of the feeding disks.

In the accompanying drawings I have illustrated my invention as applied to a machine 35 of the type just described.

The object of my invention is to improve and simplify machines of this character.

In carrying out my invention I have provided a feeding mechanism in which one of 40 the disks may be advanced or retarded in its normal movement relative to the other to full one or the other of the two edges of the work sewed together, while the other feed disk is positively locked at all times against 45 any movement other than its normal feeding movement, and this I have done by an arrangement which does not put a heavy frictional load on the feeding mechanism. I have also greatly simplified the mechanism 50 for giving the looper its necessary movements, while providing for certain desired adjustments by which the path of the looper may be varied in a way not heretofore possible.

55 My invention also comprises features of

construction and arrangement tending to simplify the construction of the machine and improve its operation while providing all necessary and desirable adjustments.

The various features of novelty which 60 characterize my invention are pointed out with particularity in the claims annexed to and forming a part of this specification. For a better understanding of my invention, however, and the advantages possessed by 65 it, reference may be had to the accompanying drawings and descriptive matter in which I have illustrated and described forms of mechanism embodying my invention.

Of the drawings, Figure 1 is a side elevation of the sewing machine proper, with parts broken away and in section. Fig. 2 is a plan view of the machine with the top frame cap removed. Fig. 3 is a front end elevation of the machine. Fig. 4 is an elevation of the adjustable bearing for the needle bar. Fig. 5 is a section taken on the line 5—5 of Fig. 4. Fig. 6 is a perspective view of the head of the needle bar with the needle secured in place. Fig. 7 is a sectional elevation on the line 7—7 of Fig. 6. Fig. 8 is a perspective view of a portion of the feeding mechanism. Fig. 9 is an elevation of one of the gears shown in Fig. 8, with the position of the meshing gear indicated by dotted 80 lines. Fig. 10 is a perspective view of another portion of the feeding mechanism. Fig. 11 is an elevation, partly diagrammatic, illustrating a modification of the looper mechanism. Fig. 12 is a view taken 85 similarly to Fig. 11, showing a third form of a looper or mechanism. Fig. 13 is an elevation taken at right angles to Fig. 12, and, Fig. 14 is an elevation of the gear meshing with the gear of Fig. 9. Fig. 15 is a front 90 end elevation of the machine proper assembled on its support.

The framework or housing of the machine comprises a main boxlike portion A, a removable front portion A¹, and a removable top cap portion A². The housing is provided with upper and lower bearings A⁴ and A⁵ for the power actuated shaft B, which carries at its upper end the feed disk C. The shaft B has a gear B² adjustably secured to 100 it by means of screws B¹. The gear B² rests upon the upper end of the bearing A⁵, and thus controls the elevation of the disk C. A spring B³, extending between the underside 105 of the bearing A⁴ and the upper side of the 110

gear wheel B^2 , holds the latter against the top side of the bearing A^5 and prevents any lost motion. To assist in adjusting the parts in assembling the machine, an adjustable step bearing in the form of screw B^3 threaded into the bearing A^5 and locked in place by a nut B^4 , may be employed. The gear B^2 is driven by a coöperating gear D , which is secured to a shaft D' journaled at its ends on the trunnion pivots D^2 which are threaded in the housing wall A and are adjustable to move the shaft D' in the direction of its length, to take up lost motion between the gears B^2 and D . Lock nuts D^3 secure the pivots D^2 in any desired position. The gear D is provided with a cylindrical flange D^4 which passes through a slot E' formed in a driving dog or member E . The member E is provided at one end with branches E^2 and E^3 which extend on opposite sides of the shaft D' . The branches E^2 and E^3 are separated by a distance somewhat greater than the diameter of the shaft D' , and a spring E^4 urges the branch E^2 toward the shaft D' . The other end of the member E is connected by a pin E^5 to a lever F into which the pin E^5 is screwed. The lever F is pivotally connected to the housing A through a fulerum F' adjustable in a slot F^2 in the lever F , and provided with a threaded extension which passes through the slot A^8 in the housing and may be clamped in any desired position by the nut F^3 . The slot A^8 is open at its forward end to facilitate assembling the parts when the frame portion A' is removed. The opposite end of the lever F to that connected to the member E is pivoted to a link G having its upper end apertured to receive the main driving shaft H of the sewing machine, which is journaled in bearings formed in the housing A . The member G is provided with lugs G' and G^2 (Fig. 3) which embrace a cam H' on the shaft H .

45 The gear D , as best shown in Figs. 8 and 9 has formed on one face adjacent its periphery a series of gear teeth D^5 . These gear teeth are V shaped in cross section, and are, in the form shown, each curved about a center, the locus of the centers being the circle D^6 of Fig. 9. The gear B^2 is provided with meshing teeth each of which is, in the form shown, divided into two parts, B^6 and B^7 , by a circumferential groove formed in the gear. 55 These teeth are also V shaped in cross section, and the crown of each tooth, B^6 and B^7 , is curved about a center which is located in the line of intersection of the plane tangent to the gear at the tooth and the plane mid-way between the two sets of teeth portions B^6 and B^7 , and at a distance from the tooth equal to the distance between the centers of the shafts B and D' . As a result of this construction, the gear D when rotated readily drives the gear B^2 , but the teeth engage in

such manner that the pressure exerted on the teeth D^5 by the teeth of the gear B^2 when the latter is acted on by forces tending to rotate it does not tend to rotate the gear D . As a result the gear D forms a lock which holds the gear B^2 against all movement other than its regular feeding movement. As the upper end of the link G rises and falls with the rotation of the shaft H the lever F is oscillated. This raises and lowers the outer end of the member E . As the member E rises the flange D^4 is gripped between the walls of the slot E' , so that the gear D and member E turn together about the axis of the shaft D , thus imparting a movement to the feeding disk C . When the upper end of the member E falls, however, the spring E^4 yields to allow relative movement of the flange D^4 and the slot E' and the gear D then remains stationary.

85 The outer feed disk C' is journaled on a shaft C^2 , the lower threaded end of which is screwed into a threaded socket formed in the outer end of the bent arm or goose neck I . The wall of the socket in the goose neck I is split at one side and the parts may be drawn together in the usual manner by a screw I' . The feed disk C' is held against displacement in an upward direction by a grooved member I^2 and screw I^3 threaded into the shaft C^2 . The member I^2 is provided with a groove I^4 in which the needle J travels and is protected. The goose neck I is secured to parallel rods I^5 and I^6 which slide in bearings formed in the housing wall A to move the disk C' toward and away from the disk C . The lower bar I^6 is provided at opposite sides with recesses I^7 which receive the bifurcations formed at the upper end of one arm of a bell crank lever I^8 which is mounted on a shaft I^9 pivotally supported by bearing members I^{10} and I^{11} carried by the housing wall. The spring I^{12} surrounding the shaft I^9 and having one end secured to the bearing member I^{10} and the other end to the bell crank I^8 , normally holds the parts in the position shown in Fig. 1 with the feed disk C' bearing firmly against the feed disk C . The tension of the spring I^{12} may be adjusted by rotating the bearing member I^{10} , which may be clamped in any desired position by a set screw I^{13} . A connecting rod I^{14} running from the second arm of the bell crank I^8 to any suitable operating device such as a lever to be operated by the knee of the operator forms a means by which the feed disk C' may be moved away from the feed disk C when it is desirable, as in entering or removing work from between the feed disks.

110 The needle J is clamped in the head J' of the needle bar J^2 by means of a movable clamping jaw J^3 and screw J^4 , (Figs. 6 and 7). A thread guide member K is removably secured to the head J' by a screw K' . The plate K , which covers portions of the front

end and side of the needle bar head, has a hook K^2 which forms an upper thread guide, and an eye K^3 through which the needle J and the thread from the hook K^2 pass. A 5 thread clamp L in the form of a headed screw or bolt passes through the plate K and the needle bar head J' . A spring L' extending between the plate K and the nut L^2 on the end of the screw L tends to hold the latter in 10 the position shown in Fig. 7, in which position the thread passing from the hook K^2 to the eye K^3 is clamped against the guide member K by the head of the screw L . A cam L^3 holds the head of the screw L away from 15 the plate K against the tension of the spring except when the needle approaches the outer limit of its movement, when the screw head clamps the thread against the guide member K and thus holds the thread tightly during 20 the final outward and initial return movements of the needle so that the stitch is properly drawn up and the loop thereafter formed is properly made. The needle bar J^2 has bearings in the front and rear walls of the 25 housing A . The front bearing J^5 is in the form of a bushing (Figs. 4 and 5) having an outer conical portion J^6 and an inner threaded portion J^7 . The conical portion J^6 has kerfs J^8 formed in it so that when the conical portion 30 is drawn home in the socket formed to receive it in the housing wall A by a nut J^9 screwed on the inner threaded end J^7 the outer portion of the bushing is contracted about the needle bar J^2 . By this arrangement 35 the lost motion between the needle bar and the front bearing, resulting from wear, can be easily taken up from time to time without disturbing the alignment of the needle bar. Longitudinal reciprocations are 40 imparted to the needle bar J^2 through a yoke J^{10} secured to the needle bar and provided with arms J^{11} which straddle the cam or eccentric H^2 on the main shaft H .

The bent looper M is adjustably secured 45 to a looper bar M' by the chuck M^3 carried by the bar M' . The looper bar M' is rotatively mounted in the looper supporting frame or member M^2 . In the form of the invention shown in Figs. 1, 2, and 3, the member M^2 is 50 provided with a slot M^4 in which is received a guide pin A^{10} carried by the housing A . The member M^2 is given movement in a direction parallel to the movement of the needle through integral arms M^5 which straddle the 55 cam or eccentric H^3 on the main shaft H . The front or operating end M^0 of the looper is caused to rise and fall at the proper time by means of an arm in the form of a disk M^8 connected to a supporting bracket M^9 by a 60 shaft M^{10} and connected by a wrist pin M^7 to an extension M^6 of the member M^2 . The bracket M^9 is secured to the housing wall by screws M^{11} and is slotted to permit vertical adjustment of the bracket. The bracket 65 may be held at different distances from the

housing by means of shims or spacers M^{12} inserted between the bracket and the housing wall. In place of this arrangement for adjusting the bracket any other well known means of adjustment may be employed. 70

By raising or lowering the bracket M^9 , the path traveled by the operating end M^0 of the looper may be raised or lowered, and by moving the bracket toward or away from the housing the elevation of the looper at the inner end of its stroke may be raised and the position of the looper at the outer end of its stroke be lowered or vice versa. By a combination of the adjustments of the bracket M^9 , in the two directions, therefore, the position of the operating end M^0 of the looper at each end of its stroke may be varied as desired. The looper bar M' is rotated to move the operating end of the looper in a direction transverse to the path of the needle by means 85 of an arm M^{12} secured to the looper bar M' and entering a recess M^{13} in the looper supporting member M^2 . This arm carries a cam roll M^{14} which enters a cam way M^{15} formed in the cam disk H^4 carried by the main 90 shaft H .

The construction shown in Fig. 11 is essentially the same as that shown in Figs. 1, 2, and 3, except that the arm M^6 of the first construction is dispensed with and the looper supporting member M^2 is connected to the arm or link M^8 by the pin M^7 at a point above the center of the looper bar M' . And I prefer the construction of Figs. 1, 2, and 3 to that of Fig. 11 because of this difference in 104 the location of the pivotal connection between the member M^2 and the eccentric disk M^8 which gives a more convenient arrangement of parts and a more desirable path of motion for the looper end M^0 . 105

In the construction shown in Figs. 12 and 13, the looper supporting member has a portion M^{16} surrounding the forward end of the looper bar M' made cylindrical to slide in a sleeve N pivotally connected to an arm N' 111 carried by rock shaft N^2 , which is oscillated through an arm N^3 and cam roll N^4 , the latter traveling in a cam way formed in a disk carried by the main shaft H . In the construction shown, this disk is the disk H^4 in which the cam way M^{15} is formed, but to avoid complications I have not attempted to show in Figs. 11, 12 and 13, the cam paths formed in the disk H^4 . 112

As shown in Fig. 15, the machine housing A is mounted on a support or table P . The rod I^4 from the bell crank I^8 extends through the support and is connected to the operating lever Q as by means of the bell crank lever O pivoted on the bracket O' secured to the support, and the rod O^2 . The lever Q , which is pivoted in the bracket Q' secured to the support P , has its operating end Q^2 extended in position to be engaged by the knee of the operator. The support or table P is carried by 13

side frames or legs P', in which is journaled the shaft R carrying the treadle R'. The latter is connected through the extension R² and connecting rod R³ to the shaft S' eccentrically carried by the pulley S journaled on shaft S² carried by one of the side frames P'. The pulley S drives the main shaft H through the pulley S³ carried by the latter and the belt S⁴. By this arrangement the operator 10 may employ both feet to rock the treadle R' and drive the machine and without removing his feet from the treadle may engage the lever Q to separate the feed disks C and C' when necessary to remove or insert work.

15 With the construction illustrated, as has been pointed out, the path of the operating end M^o of the looper can be varied as desired, as for example to make the looper act in a proper manner with needles of different 20 sizes or adjustment and with varying kinds of work. The adjustable thread guide member K and thread clamp L, which are subjected to rapid wear, may be easily replaced by a new thread guide and clamp when necessary or desirable. The feed disks may 25 readily be adjusted to the proper relation with respect to the shape and travel of the needles used. This is of importance since in machines of this type the strain on tightening 30 the stitches cannot be withstood by the fine needles employed unless the latter are properly supported by the edges of the feed disks.

The feeding mechanism is positive in its action and is so arranged that the feed disk 35 C' may be advanced or retarded with respect to the feed disk C in order to full one side or the other of the work without disturbing the position of the feed disk C, thereby insuring a proper stitch disposition 40 under all conditions. By arranging the looper supporting frame with rigidly connected cam engaging arms directly acted upon by a cam on the main shaft, the to and fro movement of the looper supporting member is obtained with a minimum number of parts, and much undesirable lost motion is 45 thereby avoided.

Having now described my invention, what I claim as new and desire to secure by Letters 50 Patent is:

1. In a sewing machine for overseaming having a reciprocating needle and a looper, a looper supporting member, means for reciprocating the said member in a direction substantially parallel to the movement of the needle, a stationary support, a link connection between said support and the looper supporting member for causing a rising and falling movement of the latter as it is reciprocated, and means for adjusting the link connection to vary said rising and falling movement.

2. In a sewing machine for overseaming having a main frame, a reciprocating needle 65 and a looper, a looper supporting member,

means for reciprocating said member in a direction substantially parallel to the movement of the needle, a support adjustably secured to the main frame and a link connection between the support and the looper supporting member for giving a rising and falling movement to the latter as it is reciprocated. 70

3. In a sewing machine for overseaming having a main frame, a reciprocating needle 75 and a looper, a looper supporting member, means for reciprocating said member in a direction substantially parallel to the movement of the needle, a support secured to the main frame and adjustable with respect 80 thereto in two directions, and a link connection between the support and the looper supporting member for giving a rising and falling movement to the latter as it is reciprocated. 85

4. In a sewing machine for overseaming having a main frame, a reciprocating needle, a looper bar, and a looper supporting member in which said looper bar is journaled, a pin and slot sliding connection between the rear 90 end of the looper supporting member and the main frame, and a link connection between the main frame and the forward end of the looper supporting member, said link connection comprising a support secured to 95 said main frame and adjustable with respect thereto in a direction parallel to the line of movement of the needle and also in a direction toward and away from the line of movement of the needle, and a link pivotally connected at one end to said support and at the other end to said supporting member, and means for giving said looper supporting member a reciprocatory movement relative to said main frame. 100

5. In a sewing machine for overseaming having a main frame, a reciprocating needle and a looper, a looper supporting member, means for reciprocating said member in a direction substantially parallel to the line of movement of the needle, a sliding connection between the rear end of the supporting member and said main frame, a support secured to the main frame, a link connection between the support and the forward end of 110 the looper supporting member for giving a rising and falling movement to the latter as it is reciprocated, and means for adjusting said support relative to the main frame in a direction substantially parallel to the line of 115 movement of the needle. 120

6. In a sewing machine for overseaming having a main frame, a reciprocating needle and a looper, a looper supporting member, a rotating shaft, a cam carried thereby for 125 directly engaging said supporting member to reciprocate it in a direction substantially parallel to the movement of the needle, a sliding connection between the looper supporting member and main frame, a link con- 130

- connection between the looper supporting member and the main frame whereby the looper supporting member is given a rising and falling movement as it is reciprocated, and means 5 for adjusting the link connection to vary said rising and falling movement.
7. In a sewing machine for overseaming, a feed disk for advancing the work, a shaft carrying said disk, a gear secured to said shaft 10 and provided with curved peripheral teeth, a second shaft extending at right angles to the first, a gear carried by said second shaft and provided with curved teeth on one face which mesh with the peripheral teeth on the other 15 gear, the teeth on the two gears being so curved and arranged that the second gear may drive the first but the first cannot drive the second, and means for intermittently advancing said second gear.
8. In a sewing machine for overseaming, a feed disk for advancing the work, a shaft carrying said disk, a second shaft, means for intermittently rotating said second shaft, and gearing connecting said shafts in such manner 20 that the second shaft can drive the first shaft but the first shaft cannot drive the second shaft, said gearing comprising a gear B² secured to the first shaft and having peripheral teeth B⁶, B⁷ and a gear D secured to 25 the second shaft and having on one face teeth D⁵ which mesh with the teeth B⁶, B⁷, the teeth D⁵ being each curved about a center, the locus of the centers being a circle concentric with the shaft D' and between it and 30 the teeth D⁵, and each tooth B⁶, B⁷ being curved about a center located in a plane tangent to the tooth.
9. In a sewing machine for overseaming, a feed disk for advancing the work, a shaft carrying said disk, a gear secured to said shaft, a second shaft at an angle to the first, a gear carried by it and meshing with the first mentioned gear, said gears having their teeth so 35 formed and arranged that the first gear can be driven by but cannot drive the second gear, means for intermittently advancing the second gear and means for adjusting said second shaft in the direction of its length to take up lost motion between the gears.
10. In a sewing machine for overseaming, a feed disk for advancing the work, a shaft carrying said disk, a gear mounted on said shaft, means for securing the gear to the shaft in different positions along the length 45 of the latter, a frame abutment on which said gear bears and a spring for holding said gear against said abutment, a second shaft at right angles to the first, a gear secured thereto and meshing with the first mentioned 50 gear, and means for adjusting said second shaft in the direction of its length to take up lost motion between the gears.
11. In a sewing machine for overseaming, a feed disk for advancing the work, a shaft carrying said disk, a gear secured to said shaft, 55 a second shaft at an angle to the first, a gear carried by it and meshing with the first mentioned gear, said gears having their teeth so formed and arranged that the first may be driven by but cannot drive the second gear, 60 said second gear being provided with a cylindrical flange portion, and means for intermittently advancing the second gear, said means comprising a dog E having a recess E' receiving said cylindrical flange and having 65 branches E² and E³ loosely straddling said second shaft, a spring E⁴ tending to urge the branch E² toward and the branch E³ away from said second shaft, and means engaging said dog and oscillating it about said second 70 shaft, whereby when the dog turns in one direction the flange will be gripped by the walls of the recess E', and when the dog is turned in the other direction the spring E⁴ will yield and the dog will not carry the gear 75 wheel back with it.
12. In a sewing machine for overseaming, a feed disk for advancing the work, a shaft carrying said disk, a gear secured to said shaft, a second shaft at an angle to the first, 80 a gear carried by it and meshing with the first mentioned gear, said gears having their teeth so formed and arranged that the first gear may be driven by but cannot drive the second gear, said second gear being provided with a cylindrical flange portion, and means for intermittently advancing the second gear, 85 said means comprising a dog having a recess receiving said cylindrical flange, means engaging said dog for oscillating it, and a spring 90 extending between said dog and said shaft, whereby when the dog turns in one direction said gear flange will be gripped between the walls of the recess in the dog, and when the dog is turned in the other direction the spring 95 will yield to permit the dog to turn without carrying the gear wheel back with it.
13. In a sewing machine for overseaming, a feed disk, means for intermittently advancing it, a second feed disk, a goose neck carrying said second disk, an extension from the goose neck slidably received in the sewing machine frame, an oscillating shaft supported in the frame, an arm mounted thereon and engaging said extension to move the second 100 feed disk toward and away from the first as the arm is turned, a helical spring surrounding said shaft and having one end fixed with respect to said arm, and a support to which the other end of the spring is secured, said 105 support being adjustable angularly with respect to the axis of said shaft.
14. In a sewing machine, a reciprocating needle bar, a thread guide member adjustably secured thereto, covering portions of the 110 front end and one side of the needle bar, and provided with an eye through which the needle and thread pass, a thread clamp in the form of a headed rod passing through said 115 guide member, a spring acting on said rod 120

35,150
tending to hold it in position to clamp the
thread between its head and the thread guide
member, and a cam intermittently engaging
said clamp to force the head away from the
5 thread guide member and release the thread.

15. In a sewing machine, a reciprocating
needle bar, a thread guide member detach-
ably secured thereto covering portions of the
front end and one side of the needle bar and
10 provided with an eye through which the nee-
dle and thread pass, a thread clamp in the
form of a headed screw passing through said
thread guide member and having a nut on its
threaded end, a spring surrounding the screw
15 and extending between the thread guide
member and the nut, and tending to hold the
screw in the position in which the thread is
clamped between the head of the screw and the
thread guide member, and a stationary
20 cam in position to engage the screw and
move it against the tension of the spring to
release the thread at regular intervals in the
operation of the machine.

16. In a sewing machine for overseaming,
25 a feed disk and connections from the main
shaft of the sewing machine for intermittently
advancing the feed disk, said connec-
tions including an oscillating dog, a lever
having one end connected to the dog, a link
30 connected to the other end of the lever, and a
cam on the main shaft acting on said link,
and a fulcrum for the lever carried by the
main frame, said fulcrum being adjustable in

slots formed in the main frame, and in the
lever to vary the amount of oscillation of said
35 dog and thereby the length of the stitch
formed, said slot in the main frame being
open at one end to facilitate assembly of the
parts, and a removable cover normally clos-
ing the open end of said slot. 40

17. In a sewing machine for overseaming,
having the reciprocating needle J, the looper
M, and a pair of feed disks C and C', the com-
bination with the machine housing A, and
the support P for the machine housing, of the
45 goose neck I in which the feed disk C' is sup-
ported, the goose neck extensions I⁵ and I⁶
slidably supported in the housing A, the bell
crank lever I⁸ for moving the goose neck to
vary the distance between the disks C and C',
50 the spring I¹² tending to move the bell crank
I⁸ to cause the disk C' to approach the disk C,
the lever Q pivoted to and extending below
the support P, the connections between the
lever Q and the bell crank I⁸ for moving the
55 goose neck I to separate the disks C and C',
the treadle R' and the connection from it for
operating the needle J, looper M, and feed
disk C, the lever Q being located in position
60 to be operated by the knee of the operator
while both feet of the operator engage the
treadle R'.

RAYMOND L. PLUMLEY.
